(57) **CLAIM**

The ornamental design for a strapless bra as shown and described.

DESCRIPTION

FIG. 1 is a perspective view of a strapless bra showing the claimed design;

FIG. 2 is another perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is a top perspective view of thereof, shown in an unfolded open configuration;

FIG. 10 is an enlarged view of area 10 shown in FIG. 5;

FIG. 11 is an enlarged view of area 11 shown in FIG. 6; and,

FIG. 12 is an enlarged view of area 12 shown in FIG. 6.

The broken lines shown in the drawings depict the boundaries of the enlargements that form no part of the claimed design.
